UNITED STATES PATENT OFFICE.

GEORGE WASHINGTON MOLLINEAUX, OF MARBLE HILL, MISSOURI.

IMPROVEMENT IN WASHING-MACHINES.

Specification forming part of Letters Patent No. 133,379, dated November 26, 1872.

To all whom it may concern:

Be it known that I, GEORGE W. MOLLINEAUX, of Marble Hill, in the county of Bollinger and State of Missouri, have invented a new and Improved Washing-Machine, of which the following is a specification:

My invention consists of a pair of horizontally-reciprocating washing or rubbing boards, suspended adjustably from slides upon the cover, with their rubbing-surfaces on the under side, to work on the top of the clothes, which rest on a stationary ribbed board, and the sides of the tub are provided with vertical ribs for acting upon the clothes. The rubbing-boards are suspended from a vertically-adjustable cross-head, mounted on rods rising up from the slides, and held down upon the clothes with the required pressure by friction-pawls on the cross-head, held on the rods by springs. The slides are worked by a lever pivoted to the top of the tub between them, so as to work them simultaneously in opposite directions. The top of the tub is hinged at one end, and held fast at the other end by a yoke, which is readily disengaged to allow the top to be lifted. The slides and rubbers swing out of the tub when the cover is raised, to facilitate the adjustment of the clothes.

Figure 1 is a plan view of my improved wash-tub. Fig. 2 is a longitudinal sectional elevation taken on the line $x x$ of Fig. 1, and Fig. 3 is a cross-section taken on the line $y y$ of Fig. 2.

Similar letters of reference indicate corresponding parts.

A is a strong rectangular water-tight box or tub, with rabbeted and grooved tongued joints, and mounted on short legs B, which are detachably connected for convenience in packing and storing compactly when not required for use. C is a stationary rubbing-board in the bottom of the box, with cross-ribs D to intensify its effect. E are vertical ribs on two opposite sides of the case for the same purpose. F denotes the horizontally-reciprocating rubbing-boards, of which there are preferably two, suspended side by side by two rods, G, to each, extending up through the slides H fixed in long slots I in the cover, to be reciprocated for actuating the rub-

bing-boards. K represents cross-heads, to which the said rods are connected. These cross-heads are mounted on the rods L, supported on the slides H, and extending vertically a suitable distance. The said cross-heads are vertically adjustable on the rods, and they have a friction-pawl, M, to each rod, with a pressure-spring, N, to bind them on the rods to prevent them from being forced upward by the clothes, whereon it is desirable that the rubbers should press with more force than their weight will cause. O denotes the actuating-lever, which is pivoted to the cover P at Q, between the slides, and connected to them by stud-pins R working in slots S. The cover is pivoted or hinged to the box at one end, and at the other end has a yoke, T, arranged with it, and pivoted to the box so as to swing up over the top and bind it down securely. U is a rest for supporting the top when raised up to put in or take out the clothes. W is a spring for holding the stationary board in the water on the bottom to prevent it from floating, and arranged to allow of readily detaching the board when required.

Having thus described my invention, I claim as new and desire to secure by Letters Patent—

1. The combination, with a wash-tub, of one or more horizontally-reciprocating and vertically-adjustable rubbing-boards, F, substantially as specified.

2. The lever O, pivoted to the stationary cover P at Q and to the alternately-reciprocating slides H by stud-pins R working in slots S, all combined as specified.

3. The combination of the said reciprocating rubbing-boards, the slides H, rods G, cross-heads K, and rods L, substantially as specified.

4. The combination, with the rods L and the cross-heads K, of the pawls M, and pressure-springs, substantially as specified.

5. The slides for supporting the rubbing-boards and actuating them, arranged on the top of the tubs, substantially as specified.

GEORGE WASHINGTON MOLLINEAUX.
